Primary Examiner — Richard Edgar*Assistant Examiner* — Courtney J Clark-Rasheed(74) *Attorney, Agent, or Firm* — Ricky Lam(57) **CLAIM**

The ornamental design for pouring shield for mixer as shown and described.

DESCRIPTION

FIG. 1 is a top perspective view of pouring shield for mixer showing my new design;

FIG. 2 is a bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is an enlarged view of a portion labeled as "9" on FIG. 1; and,

FIG. 10 is a top perspective view, showing the pouring shield for mixer in an opened configuration.

The dot-dash broken lines in the drawings illustrate the boundaries of the portions shown enlarged in the drawings and form no part of the claimed design.
